L. DAHLGREN

SEPARABLE CUFF BUTTON

Filed April 4, 1925

Inventor

Leonard Dahlgren

By Joseph A. Miller

Attorney

UNITED STATES PATENT OFFICE.

LEONARD DAHLGREN, OF ATTLEBORO, MASSACHUSETTS.

SEPARABLE CUFF BUTTON.

Application filed April 4, 1925. Serial No. 20,671.

To all whom it may concern:

Be it known that I, LEONARD DAHLGREN, a citizen of the United States, residing at Attleboro, in the county of Bristol and

5 State of Massachusetts, have invented new and useful Improvements in Separable Cuff Buttons, of which the following is a specification.

This invention relates to certain new and 10 useful improvements in separable cuff buttons, and the primary object thereof is to provide a button wherein the male and female members are connected by axial movement between the members.

15 The invention further aims to provide means for separably connecting the members, which is of simple and economical construction, and which involves a minimum of parts.

20 The invention has still further and other objects which will be later set forth and manifested in the course of the following description.

In the drawings:—

25 Figure 1 is a side elevation partly broken away and in section, showing the members connected.

Figure 2 is a section on line 2—2 of Figure 1 and

30 Figure 3 is a view similar to Fig. 2, showing the members relatively turned.

In proceeding in accordance with the present invention, the male member has an outer head 1 and an inner head 2 connected thereto by a web 3. A stem or shank 4 is secured to the head 1 and the tubular part 5 of the web 3 and has a cone-shaped free end or head 6. The head 6 is formed with a pair of opposed slots 7 providing a pair 35 of parallel walls 8 that are located at the base end of the conical head 6, the walls 8 being tapered and forming continuations of the taper of the head 6.

40 The female member has an outer head 9, and an inner head 10 the latter formed with a guiding neck 11 that projects into an opening 12 provided therefor in the head

2 of the male member. A web 13 connects the heads 9 and 10 has a hollow cylindrical central part 14 in which the head 6 of the 50 male member is received.

A substantially C-shaped wire or other 55 spring 15 is secured between the inner head 10 of the female member and the flared part 16 of the web 13 and has its ends formed with inturned parallel parts 17, which latter are adapted to snap into the slots 7 when the head of the male member is moved into the female member, the cone shaped head 6 forcing the end parts 17 of the spring 60 away from each other during insertion of the head 6, until the slots 7 of the head register with the spring ends 17, at which time the latter will snap into the slots and thus latch the parts together.

65 To disengage the members, it is merely necessary to effect relative turning movement therebetween, which causes the walls 8 of the head 6 to force the spring ends 19 apart, as depicted in Figure 3 whereupon 70 the spring ends will ride on the taper of the walls, and encountering the inclined periphery of the head 6, will naturally ride therealong and thus force the two members 75 relatively apart.

The webs 3 and 13 hold the button against turning in the buttonholes of the cuff, so as to permit of removal of the button by use of but one hand.

It will be observed that the sole or single 80 movable element of the structure is that of the spring, which latter is secured in position, thus providing a simple, economical and compact construction.

Having thus described my invention what 85 I claim as new and desire to secure by Letters Patent is:—

1. In a cuff button, a male and a female member each having an inner and an outer head, said male member having a stem 90 formed with a cone-shaped end, said end being provided with opposed slots between its tip and base to provide a pair of tapered end walls, and a spring device carried by

the female member and having parts receivable in said slots, said stem being turnable in the female member whereby upon turning to spread said spring parts by the tapered end walls thereof to cause the spring parts to ride on the tapered end walls and thence on the end of the stem to separate the members, and a web connecting the heads of each member and shaped to hold the members against turning in the buttonhole.

10 members against turning in the buttonhole.

2. In a cuff button, a male and a female

member each having an inner and an outer head, a web connecting the heads of each member and shaped to hold the members against turning in the buttonhole, means to connect the members and means whereby to effect separation of the members by and upon relative turning movement thereof.

15 In testimony whereof I have signed my name to this specification.

LEONARD DAHLGREN.
